METHOD OF COLOR CORRECTION OF PHOTOMECHANICAL IMAGES

Robert L. Klein, Cincinnati, Ohio

Original application March 20, 1935, Serial No. 12,032. Divided and this application October 21, 1937, Serial No. 170,211

10 Claims. (Cl. 95—5.1)

This is a division of my copending application Serial number 12,032, filed March 20, 1935.

The present invention relates to the color correction of half tone negatives used in the preparation of lithographic color plates and has for an object the provision of novel method and means that will enable the process artist to do all work on the negative and to quickly and effectively produce corrected photo-lithographic negatives that produce results equal or superior to anything that the engraver can produce with his engraving plates.

Another object of the invention is to provide a method and means whereby the process artist can with a minimum of time and effort modify the color printing values or tonalities of negatives of all kinds that are employed in lithographic work, including the dot etching of masses on the negative from a solid color to a pin dot or vice versa.

Another object of the invention is to provide a method and means whereby the tonality corrections by the process artist on the negative are permitted to remain permanently on the negative so that the plate maker may print the negative on paper or zinc without removing any portion of the materials applied by the artist and whereby these materials remain as a means affording a high degree of protection for the preservation of the negative against atmospheric and other deteriorating conditions.

Another object is to provide a method and a system of opaque and transparent staging solutions that afford the process artist a maximum of facility and speed in preparing negatives of this character for the plate maker as well as for permanently preserving the negative for future reprints on zinc.

Another object of the invention is to provide a method and means whereby all work on projection prints may be done on a small negative, thereby eliminating crayon work after the print on zinc is made.

These and other important objects are attained by the means and method hereinafter described and schematically illustrated in the accompanying drawing, in which:

Figs. 1 and 2 represent greatly magnified schematic illustrations of the penumbra or shadow that appears around the half tone dots on the negatives.

Fig. 3 illustrates schematically a single magnified and unclarified half tone dot with its penumbra.

Fig. 4 is an enlarged representation of the half tone pattern or mass on a negative as it appears when used in a bright light.

Fig. 5 is a view of the negative as shown in Fig. 4 when the same is held in a subdued light, showing the edges of the individual dots as they

appear to fade into the penumbra and lose their corner to corner connection.

Figs. 6 to 11 form a continuous schematic view showing the steps of dot etching of the invention from a solid color to a pin dot and reverse on a negative, these views further representing the negative as being one-half staged with the staging chemical solution of the invention having a one-quarter tint of dye therein, and the other half etched with acids.

In the following disclosure the term "negative" as used in a general sense includes dry plates, wet plates, films and even screen projection negatives, in other words, all negatives employed for preparing color plates in the so called photo-lithographic process work that always require the efforts of a process artist in correcting the color printing values or tonalities of any such negatives.

In its broad aspects the invention herein includes a method and means constituting a dot etching system of correcting half tone negatives, staging the same with staging solutions and chemical resists, etching and re-etching with acids whereby the process artist has complete control of the tones to be corrected to the same extent as the photo-engraver has with his copper plates. This includes the etching or reducing where necessary from a pin dot to a solid mass or reverse and also the intensification of tonalities wherever desired by the application of water and acid resisting transparent staging solutions containing aniline dyes of colors to produce the necessary corrected color printing values on the negative; and also the staging with a clear transparent acid resist staging compound to retain any corrected masses against further reduction.

The methods employed by the process artist in correcting half tone negatives have heretofore required a considerable amount of time and tedious painstaking effort including hand engraving and uncertain etching and has been beset with numerous aggravating difficulties. The purpose of the present invention is to minimize the difficulties and to reduce the cost of production of such negatives in time, money, and labor from thirty-five to forty percent, and to further enable the process artist in many instances to reduce the number of color plates required by reason of vastly superior negatives such, for example, as would enable the lithographer to produce what has all along required a seven color job in only four colors, thereby further and materially reducing the cost of the job. The same advantages apply to all negatives that are used for any purpose in lithography such as continuous tone positives, etched positives, etched and staining contact positive, direct or contact negative printing, projection work from small negatives that are enlarged and printed on zinc, and

for methods of the so called deep etched lithography, the application of this invention to all of these being readily understood by those conversant with the several phases of the art connected therewith. The double printing of color corrected dry plate negative and line negative on the zinc plates is eliminated by the system of the invention because, in stripping the desired portions of one negative to insert in stripped portions of another negative, the edges of the emulsion are firmly held down with the clear staging solution which prevents their curling up and this also forms an excellent base over which the opaque staging of the invention may be applied. The so called dry plate negatives have been considered desirable because of the greater fidelity obtainable therewith but have been costly when prepared according to known methods in the past especially because of the large amount of work required thereby and the consequent lack of speed in producing them. The system of the present invention is therefore particularly advantageous when used on dry plates.

For carrying out the system or method of this invention, there has been provided a novel acid and waterproof clear transparent liquid staging solution having controllable quick drying properties which is usable as such to protect the originally correct and subsequently corrected half tone masses of a negative and which is furthermore adapted to have admixed therewith quarter, half, and three-quarter tints of aniline dyes of warm colors such as carmine, scarlet, orange, scarlet red, and lustre red, finely powdered aniline dyes which enable the process artist to at one operation protect the half tone dots and reduce the tonality of the negative to the proper degree of color, either originally or for the purpose of correcting the result of too much etching of the negative.

At this point it is to be noted that satisfactory staging chemical resist compounds, whether clear transparent, stained and translucent or opaque must be free flowing from a brush and capable of uniform application in large or small masses, even down to a hair line with the brush. The results must be free of clouding or spotting and must not crack or show pin holes. In order that the print on paper or zinc may be made without removing the staging compounds they must not deteriorate when subjected to strong etching acids. The hereinafter described staging compounds have the desired properties which make possible a heretofore impossible rapid and money saving system of color correcting negatives.

For this clear transparent staging solution I employ a liquid Celluloid base and a suitable solvent and thinner. The preferred form of transparent acid resisting liquid staging is made by dissolving Celluloid, e. g., the finest grade of transparent sheet Celluloid in acetone. The liquid Celluloid ingredient is made by dissolving the sheet Celluloid in enough acetone to provide a solution that is free flowing from a painter's brush. A quantity of this solution is then mixed with substantially an equal part of amyl acetate (Merck). The resultant transparent acid and water resisting staging solution when applied to the half tone spot on a negative serves to clarify the dot by dissolving a very slight amount of the thin scum or fringing materials which otherwise produce the penumbra on printing and at the same time renders the mass covered thereby otherwise unchanged except that the dots are

definitely and permanently protected against the effects of the etching and other solutions used in correcting negatives.

The clear transparent Celluloid base staging solution is quick drying. Acetone is its solvent and thinner. If a large mass on the negative is to be covered it is sometimes desirable to retard the speed of drying. This is important when stain or dye is mixed with the clear staging as it avoids double staining in the overlapping brush strokes that would be reproduced in the staged mass. The speed of drying is retarded selectively by mixing with five (5) parts of the Celluloid base staging solution one (1), two (2), or three (3), parts of a solution of copal gum dissolved in acetone. It is deemed important to avoid mixing more than three (3) parts of copal gum solution with the staging solution in order to avoid the appearance of a "sharp" edge on the staged mass by reason of an actual excessive thickness of the staging.

This clear transparent Celluloid base acid resist staging may have a very slight tint of ultramarine or cobalt blue aniline dye added thereto in order to enable the artist to more readily see his work under unsatisfactory light conditions and without materially altering the tonality of masses staged therewith.

It is also possible to intensify or darken a half tone mass on the negative by applying selected tints of water stain of aniline dyes of warm colors and then protect this work with a coating of the clear transparent staging solution.

For simultaneously clarifying, intensifying and protecting a half tone spot, I have provided a staging solution of the same Celluloid base but which has admixed therewith aniline stain of the desired color and tint as aforementioned. This is prepared substantially as follows.

A thick water paste is made of the aniline dye, e. g., scarlet or lustre red, 95% proof denatured alcohol is slowly added, keeping the mixture warm at low heat. The mixture is then cooled and filtered several times, after which one-twentieth of a per cent of acetone is added. The resultant mixture is then heated to about a luke-warm temperature and again filtered whereupon one-half part each of amyl acetate and the dissolved Celluloid is added to the strong stain and kept at a mild heat for about five minutes more or less after which the same is allowed to cool and is well shaken. Various lighter tints of this reducing and staging solution can now be produced by the artist who will mix the desired quantity of the aforesaid solution with the clear transparent staging solution aforementioned. The advantages attending the use of the waterproof and acid-proof transparent stained staging solution will be readily appreciated by those conversant with the art in view of the foregoing remarks. It is to be noted, however, that in practice the blending of tonalities can be attained and sharp lines between adjacent masses on the negative can be avoided by vignetting the differently stained masses in the following manner.

The artist applies the desired differently stained or the clear and stained, transparent staging solutions to the respective areas but leaves an uncoated margin between them whereupon he skillfully blends the two masses before they are dry with the aid of a brush dipped in clear transparent Celluloid staging solution. It will be noted that the process of applying the staging solutions partakes of the characteristic of applying color to wash drawings.

On the half tone negatives the white portions of the original drawing, including the usual surrounding border, do not photograph on the negative correctly, hence these portions must be opaqued by coating them with a waterproof and chemical resisting opaque staging solution. By opaquing before the first etching operation it is relatively easy to perfectly preserve fine outlines on the negative that are hardly visible.

10 It is one of the refinements of the system of this invention to provide an opportunity for the artist to avoid conditions where adjacent and meeting staged and opaqued masses have the same solvent in common because, if corrections are required that include removing some of the staging or opaque solution, the artist might disturb some of his previous corrected work. This detrimental result is avoided by providing several opaque waterproof chemical resisting solutions, one of which has acetone for its solvent and the other of which has turpentine for its solvent. As a further aid to the artist the system also provides a third opaque staging solution which utilizes hot alcohol (denatured) as its solvent. The transparent (clear and stained) staging chemical resist utilizes acetone for its solvent, hence the turpentine soluble opaque waterproof and chemical resistant staging compound would be indicated for use adjacent these masses on the negative that have been or are to be staged with clear transparent or stained Celluloid base staging compound. The solvent in each of the said staging compounds is ineffective on the other. The third type of opaquing compound is not recommended for use any time prior to the final etching operation.

15 Since the clear and stained Celluloid base staging solutions as well as the several opaque staging solutions are all relatively quick drying, they do not delay the artist for any appreciable length of time in the correction of his negatives.

20 The several opaque staging solutions are made substantially according to the following formulas:

Celluloid-base opaque solutions

	Ounces by weight
Clear Celluloid solution (consisting of 1/2 Celluloid dissolved in acetone and 1/2 amy1 acetate (Merck)	1
Free flowing solution of copal gum and acetone	1
Opaque material dry (selected for contrasting visibility)	8
The three preferred solution according to this formula utilize 8 ounces of lamp black for black Celluloid opaque solution, of 8 ounces of finely ground zinc white for a white colored Celluloid opaque solution, or 2 ounces of said zinc white and 6 ounces of lamp black to make a grey Celluloid opaque solution. In all cases acetone is the thinner and solvent. The quantities of the several ingredients may be varied somewhat.	

Turpentine soluble opaquing solution or black amber opaque solution No. 1

Amber (fossil resin)	8 ounces by weight
Lamp black	8 ounces by weight
Japan drier	2 ounces by weight
Boiled linseed oil	4 1/2 ounces by weight
Gum dammar and/or gum mastic	4 1/2 ounces by weight
Turpentine	about 1/2 pint

The amber is reduced to a semi-liquid by heating, after which the boiled linseed oil is added and

well mixed therewith. This is then allowed to become lukewarm, after which turpentine with the gum or gums first dissolved therein is stirred in lamp black is added and mixed therewith.

Turpentine is used as a thinner when needed and as a solvent for removing this opaque medium from the negative if necessary.

Black amber opaque compound No. 2

This is made substantially like the No. 1 formula but omits the gum dammar, and/or gum mastic.

Another turpentine soluble opaque staging compound

Parts by volume
Lump pitch (heavy street lump tar) melted
Lamp black
Japan drier
Turpentine as needed for a thinner.
Gum dammar and/or gum mastic may be incorporated up to 1/4 the volume.

The heavy pitch is melted to a thick liquid with a little turpentine added. Then when partly cooled the Japan drier is added. The lamp black is then thoroughly stirred in and enough turpentine is added to provide the desired brushing consistency. Turpentine is used as a thinner and as a solvent.

All of the foregoing opaque compounds are both water and acid resistant and when applied to a negative form a thoroughly and completely opaque coating that does not crack or show pin holes. The negatives treated therewith remain intact during wide temperature and moisture variations so that no great care, other than guarding against undue scratching, need be exercised in storing away the negatives for future use and reuse.

Black waterproof opaque

Ounces by weight
Shellac (clear or orange) liquid
Borax (variable)
Water
Gum arabic
Gum dammar dissolved in hot alcohol
Lamp black as needed.

The borax and shellac are boiled and when dissolved are allowed to cool and the twenty ounces of water are added together with three ounces of gum arabic dissolved in warm water. Then the three ounces of gum dammar dissolved in hot denatured alcohol is added. Lamp black is then added, while stirring, in a quantity sufficient to produce a medium thick liquid. Dissolved gum mastic and/or copal gum are optionally added in this mixture.

This formula is valuable in many instances and is particularly useful after all etching has been done on the negative. All of the other opaque compounds may be used at any time, i. e., either prior to the first etch for preserving the outline of delicate tone masses that might be lost on the first etch or at any other time. The ability to utilize staging chemical resist that are differently soluble and which are or may be made visibly distinguishable is of great value to the artist.

The clear and stained transparent staging compounds hereinbefore disclosed do not cloud or fog on the negatives nor do they have any inherent tints therein which would detrimentally alter printing values of the negative. It has been found that while many apparently clear transparent lacquers and kindred products are avail-

able on the market for other purposes, all of the many varieties tested have proved unsuited for the purposes of this system of staging negatives either by reason of a resultant foggy appearance or because of unsuitable light transmitting properties due to color tints that are detrimental.

The system employing the foregoing novel chemical resist staging solutions and opaquaing solutions can be comprehensively outlined by a description of the same as applied to any one negative of a set of negatives that would be required to be made and corrected for producing a set of color printing plates such as zinc plates. According to the present system, it is to be noted that one negative is sufficient for each color plate in contradistinction to certain practices now in vogue. It is to be noted also that at no stage during the correction of the negative is it necessary to remove any of the solutions placed on the negative by the artist. Hence a great deal of time and labor is saved. It is further to be noted that the plate maker prints his zinc plates from negatives with all of the artist's work, i. e., all chemical staging resists of clear, tinted or opaque types remaining thereon and, if after proving certain retouching and corrections are necessary, they may be accomplished in practically every instance without disturbing those masses that are deemed to be correct on proving.

Assuming now for example that the artist has before him the negative or so called yellow plate for a multi-color job. The artist first opaques the border section and any masses which in his judgment should show no yellow whatsoever by opaquaing over such masses with the amber base or tar base opaque solution which are soluble in turpentine. These masses preferably include masses that are to remain white or are to be printed in color tints which might work out undesirably if printed over yellow. Thus with a few strokes of the brush the artist has on the first staging operation definitely and permanently deleted those masses that are to contain no yellow, including those masses that are to contain no color whatsoever. The choice of opaques affords ample opportunity for the artist to expedite his work and also to save his eyes.

The artist next examines the tonality of the half tone spots with a magnifying glass, comparing these masses from time to time with the original painting, color sketch, or the like. The originally applied turpentine soluble opaque or other opaques used are soon dried and the artist now selects those half tone spots that have in his judgment photographed correctly, i. e., will produce the desired degree of tonality for the color then under consideration which in this case is yellow. These originally correct masses he brushes over or coats with the clear transparent Celluloid base staging solution and thereby at once clears up the half tone dots and preserves the masses against the action of chemical solutions in the further preparation of the negative. If the light conditions under which the artist is working are occasionally or characteristically poor, the artist is materially aided in seeing the extent of clear transparent staging if a slight tint of ultramarine or cobalt blue aniline dye tint is added to the clear staging solution. This does not affect the light transmitting properties of the staged mass on the negative. Next those various tone masses are again carefully scrutinized to determine whether the photographer has overexposed and overdeveloped or whether the negative is weak by reason of lack of development or

by using poor chemicals or poor developer and also whether the negative is subject to any of the other faults such as underexposure and/or overdevelopment. The process artist must be prepared to correct his half tone negatives for all of these faults as well as for the mechanical difficulties due to the fact that the normal camera work now obtainable with color filters is but approximately forty per cent correct for tonality and color values. After first staging or coating the initially correct tone masses with transparent Celluloid base staging solution, the artist next selects the half tone masses that appear to be too open on the negative and therefore allow too much light to pass through. Over these masses he places a coating of Celluloid base clear staging solution with aniline dye stain therein, selecting or mixing such solutions so as to add a light or heavy quarter tint, light or heavy half tint, or light or heavy three quarter tint to the mass as originally photographed onto the negative. Where blending of tonalities is required to avoid undesired abrupt edges of the masses, the vignetting to the edges of such masses is accomplished as heretofore described. After the artist has applied the opaque, clear, and stained chemical resist staging solutions and in some cases has stained with clear aniline stain or dye and staged over with clear transparent chemical résist to eliminate, retain, and modify the color printing values on the negative, he is ready to attend to the etching of various masses that require opening up, i. e., to have greater light passing values, by etching to a desired density. For this purpose the artist has left free of staging (1st) all of those masses that are required to be etched to clear glass, and which will represent solid color on the zinc plate, (2d) all masses requiring the photogravure's pin dot, and (3d) all other uncorrected masses that require some degree of additional etching with chemicals to intensify the given color on the zinc plate.

The next operation is the first etching operation. According to this system, the etching is desirably carried on in glass trays having strong light shining through from beneath them so that the artist may observe the progress and rapidity of the etching with a magnifying glass without the necessity of frequent removal of the negatives from the solution. The artist is now ready to etch. After a preliminary soaking of the negative in water, he places it in a solution of thiosulfate of sodium and water and allows it to soak for about three to five minutes. Then putting the negative in a solution of ferricyanide of potassium and water, he studies the gradual etching of those areas that require the slightest amount of etching. This cutting removes the penumbra from around the black dots and the white dots are made larger and if allowed to continue its action the "black dots" on the negative become smaller. When sufficient cutting has eventuated for the lightest etch, the same is placed in a second bath, usually thiosulfate of sodium one ounce, and water sixteen ounces, which stops the cutting action of the first bath and clarifies it, i. e., removes yellow stain that may have been caused by incomplete washing by the photographer when the negative was dried. As soon as the negative has cleared in the thiosulfate of sodium and water solution, it is removed and placed in a bath of running water until well washed, whereupon it is allowed to dry, preferably in a place of uniform temperature and atmospheric condition, if available. After the first etch has been completed as

aforesaid, the artist now stages over all the corrected tone masses as compared to the same masses of tone on the sketch with clear transparent staging solution or, in the event certain masses have been etched too much in the first 5 operation, the clear transparent Celluloid staging has suitable tints of red aniline dye admixed therewith before application in order to rectify the effects of over-etching. As previously stated, 10 a slight amount of ultramarine blue or cobalt in the staging solution is advisable in lieu of using clear transparent Celluloid staging solution when the masses may be difficult to see because of poor light conditions. The negative may require one 15 or several more etching operations, particularly when etching to solids or clear glass between which operations the negative is staged with clear or tinted transparent staging solution on those masses that have been at least sufficiently 20 etched. These alternate operations are carried on successively in very much the same general order as the photo-engraver etches, stages, and re-etches his heavy zinc or copper plates. The 25 Celluloid base transparent solutions may be termed a permanent liquid transparent chemical resist staging solution capable of color modification for reducing in desired degree the color printing tonality values on the negatives.

It is also understood that retouching with etch 30 solutions or acids, using brushes or wads of cotton rolled on the brush handle or any larger masses may be resorted to for the purpose of eliminating the so-called hard lines between tone 35 masses. This is accomplished by having the negative fairly damp with a solution of thiosulfate of sodium and water, and by thereafter swabbing over the mass to be etched with cotton or a brush carrying said thiosulfate of sodium solution and then with another brush or cotton wad carrying 40 ferricyanide of potassium solution, swabbing over the half tone mass and testing the same from time to time with a magnifying glass to determine when the mass is sufficiently etched. Then this mass or these masses are again 45 swabbed over with thiosulfate of sodium solution to stop the etching and clarify the mass of half tones. The staging with a Celluloid base transparent staging solution is then effected in a manner hereinbefore described, any excess etching being readily correctible with the transparent 50 Celluloid base staging solution having the dye tints therein.

Thus the process, particularly in mass reduction of tonality of the masses of the half tone negative, resolves itself into a series of successive 55 staging with the staging solutions, or chemical resists, etching, staining, and vignetting the various masses of tonality.

It is considered desirable after staging the negative to place the same in a bath of clear water for about forty-five seconds, then in a bath of thiosulfate solution for about fifteen seconds, after which it may be placed in the etching acid, e. g., ferricyanide of potassium solution until the 60 desired degree of etching has been accomplished.

A great deal of time is saved in these processes due to the fact that after the etching step has been completed and the negative has been put in the thiosulfate of sodium solution to stop the 65 etching, the negative may be placed in a running water bath for about five minutes, removed and partly dried. With the negative still damp, it is possible to almost immediately proceed with the next staging operation, thus carrying on the operation by the required steps of vignetting, etching 70

with solutions, etc., upon the negative, producing all the required tonality values from the so-called "engraver's pin dot" down to quarter, half, three quarter, or to clear glass. A vast saving of time is effected because the chemical resist staging 75 solutions, either clear transparent, stained transparent, or opaque, all remain on the negatives so that the plate maker does not have to remove them before making prints on zinc or paper; nor need any correct work be removed or spoiled in 10 making final corrections and in touching up the negative after proving same on the proving press.

By reason of the fine degree of control available to the process artist by the use of the system and the novel staging compounds of the invention, it is possible to retain all of the desirable features 15 that are attained, on a dry plate negative, all the features of merit that reside in the plate maker's engraving system, in the wet plate or film system, and also deletes substantially all 20 those features that have heretofore caused the so-called dry plate system of process engraving to be so expensive, tedious, and time-consuming.

While the foregoing examples of operations 25 have been explained in connection with the dry plate system or process lithograph engraving, it is to be understood that substantially the same operations are readily adapted to the use of the process artist on all manner of wet and dry plate and film negatives as well as projection negatives 30 of various kinds that are known to photolithography. The same advantages obtain throughout. No crayon work is required on the projection after the print is made on zinc or paper. The work is all done on the negative 35 before printing and all chemical resists remain permanently on the negative.

The system of the present invention eliminates the necessity for double printing of negative plates. The difficulties heretofore experienced 40 in stripping work such as type of various sizes on half tone dry plate negatives is completely avoided because the staging solution, either clear, tinted or stained, or opaque, all serve to literally glue down the edges which are prone to curl up on 45 one or both sides and which preclude later applied opaquing from seeping under such edges in a manner well known and highly disagreeable to the artist.

The method and means of the invention are 50 well adapted to production of the so-called "deep etched plates" because the chemical resist staging solutions remain on the negative after the deep etched plates are made, thus saving the fully corrected negative for reprints on zinc if the 55 plates are ruined on the press.

In projection negative work, e. g., 300 line screen or 175 line small sized screen negative, the usual large amount of crayon artist work is deleted. Likewise, if a plate is spoiled on the 60 press by being gum streaked, it is possible to quickly make another printing plate in a matter of an hour or so because the negative is intact as originally corrected and all of the grievous delays and work have been avoided. As final 65 corrections are frequently required after proving various negatives, it is not to be overlooked that staining down and blending and vignetting may be put in with water soluble aniline dye and then protected when finally correct with a brush 70 coating of clear Celluloid base staging solution. It will be apparent to those conversant in the art that with the means and method of the invention making up this system, it is possible to effect with one set of negatives a job that would 75

require the negative-positive-negative system according to previously pursued methods.

Summarizing the advantages attending the use of the means and method of the present invention, there is to be noted the following. 1. A lesser number of negatives is required to be made for each color actually used than with previous system. 2. The time required to make a given negative is materially reduced because there has been eliminated the heretofore time-wasting operation of removing the chemical resist before each successive operation. 3. Staging compounds of the Celluloid base group permanently save and clarify the half tone mass and, in the case of the tinted solutions, they also reduce it all in one operation. 4. The opaque is also a permanent and protective addition to the negative. 5. The character of work obtainable with half tone negatives according to this system enables the artist to produce a multi-color job with a lesser number of negatives, for a lesser number of colors in many instances. This reduction in cost is manifolded because it also entails fewer negatives, fewer corrections, fewer print plates, fewer colors of ink, and fewer press operations.

The method and means of the invention will tend to render more commonly available, because of materially reduced expenses in the production thereof, reproductions having a high degree of fidelity in color tonality.

Reference is made to the drawing which represents schematically and on enlarged scale the character of the factors of the negative, particularly the half tone masses. Figs. 1 and 2 merely represent schematic enlargements of the penumbral area about the black dot and sometimes greatly limiting the white dot. Fig. 3 shows an enlarged schematic representation of a black dot and its penumbra. Looking through a half tone mass on the negative against strong light the characteristic checkerboard design as in Fig. 4 is noted. The black dots 15 and the white dots 16 appear square and connected corner to corner. The same mass viewed in a more subdued light appears as black and white round dots 17 and 18, respectively, with a light penumbra 19 between them as in Fig. 5.

In the connected series of Figs. 6 to 11, the masses of graduated tonality are shown from a solid to a pin dot. The left hand longitudinal side A—A shows the various tints staged with the transparent staging chemical resist with a $\frac{1}{4}$ tint of dye in it; thereby holding these different tonalities against the action of etching solutions. The remainder of the continuous series, namely, section B—B shows the effect of etching on the unstaged parts of the negative compared with the parts that were staged before placing the negative in the etching solutions.

For example in Fig. 6 A—A is one-fourth tint value while B—B has been etched to enable printing as a light or heavy "engraver's" pin dot.

Fig. 7 shows at A—A a heavy quarter tint of tone while B—B shows a similar mass after etching with acids to a tone that may be printed on zinc as either a light or heavy one-fourth tint.

Fig. 8 shows at A—A a half tone mass and at B—B the same value mass after etching with acids to be printable as a heavy one-half tint or a light three-fourths tint.

Fig. 9 shows at A—A a half tone mass and at B—B the same mass etched with acids to print as a light or heavy three-fourths tint.

Fig. 10 shows at A—A half tone mass and at

B—B the same mass etched to be printed as a very heavy three-fourths tint.

Fig. 11 shows solid black on the negative.

As etching of untreated or unstaged masses is continued the black dots are etched away to progressively smaller size and if continued the dots will be completely etched away to clear glass. Since the permanent staging of transparent Celluloid base solution may be applied to any of the half tone masses that are correct originally or after one or more suitable etching operations the original imperfect results of camera photography can be corrected as to desired masses while others remain unchanged by the etching solutions. Where the negative is not dense enough to produce the desired tonality either due to imperfection of the camera and filter process or due to inadvertent or unavoidable excessive etching with acids the fault is readily correctible by the artist who preferably uses the transparent Celluloid base chemical resist staging solution with the proper tint of aniline dye stain therein but may, where desirable, stain with the proper tint of the aniline dye stain alone and subsequently protect this stained mass with clear transparent Celluloid base staging solution. The permanent opaque solutions of the invention are all capable of solid permanent coverage on the negatives in masses from a hair line brush mark to a large mass.

The materials employed in the system herein are all relatively harmless to the health of the artist. The permanent nature of the coatings of opaque, clear transparent and stained transparent staging avoids the difficulties attending the correction of many delicate masses by the superimposed negative method.

The formulas given herein represent highly satisfactory products for the purposes mentioned and are to be considered as not strictly limited to the exact details given since they may be varied within limits without materially sacrificing the desired and/or necessary properties which render them useful in carrying out the system of the invention.

The keynote of efficiency in the system is the utilization of permanent staging of the several types whereby the desired masses are retained at correct values without need of removing the staging and the ability to proceed with the correction of the negative rapidly without necessity of any intermediate steps of removing the chemical resist staging except for correcting definite error on the part of the artist. If such error occurs the rectification is easy and speedy and need never entail the spoilage of negatives. The several solvents for the several staging compounds are ineffective on other adjacent work if the artist has used reasonable judgment in correcting the negative according to this system.

In addition to the correction of negatives, the zinc press plates are protected against oxidation which occurs frequently on long storage after use, in spite of the gum arabic solution commonly used, by adding over said gum arabic solution a coating of my Celluloid base staging solution diluted with a large amount of acetone, e. g., 16 parts acetone to one part of the solution of $\frac{1}{2}$ amyl acetate and $\frac{1}{2}$ sheet Celluloid dissolved in acetone. When the press plates are again to be used the protective Celluloid staging film is removed by washing with acetone and then the gum arabic coating is washed off with water and the plate is rolled up with ink ready for the press.

What is claimed is:

1. The method of controlled color correction of photomechanical images which comprises the steps of applying, over those mass tones that are correct, a permanent transparent waterproof and acid-resisting staging compound, etching unstaged tone masses of the image with etching solution until masses requiring the least etching are corrected, then staging the masses thus corrected with permanent transparent waterproof, acid-resisting staging compound, repeating the etching and staging operations as required to correct and protect all tone masses of the image, then photographically copying through the corrected image without removing any of the previously applied staging compound.

2. The method of controlled color correction of photomechanical images which comprises staging tone masses of the image that are correct with a waterproof acid-resisting Celluloid base quick drying liquid chemical resist that forms a transparent permanent protection for such masses, and successively etching with chemicals and staging other masses to effect alterations of the image masses from a solid to the engraver's pin dot as required, then photographically copying through the image without removing the chemical resist.

3. The method of controlled color correction of photomechanical halftone images which comprises staging tone masses that are correct with a thin, permanent coating of waterproof and acid-resisting transparent staging compound having acetone as its solvent for simultaneously clarifying the dots and protecting said tone masses against chemical etching, and photographically copying through the image without removing the staging compound.

4. The method of controlled color correction of photomechanical images which comprises the steps of staging tone masses requiring intensification with a waterproof, acid-resisting Celluloid base acetone soluble staging solution having a selected tint of known actinic light retarding dye therein to simultaneously clarify and correct the tonality of such masses and protect them against attack by etching chemicals and the deteriorating effects of atmospheric conditions and then photographically copying through the image without removal of the previously applied staging.

5. The method of color correction of photomechanical images which comprises applying a thin permanent glossy coating of waterproof and chemical-resisting opaque compound to those masses on the image that are to be without color value, then photographically copying through the corrected image without removal of the opaque resist.

6. The method of deleting all color value from a selected mass of a photomechanical image which comprises coating such mass of the image with a thin glossy permanent, Celluloid base, waterproof, acid-resisting opaque staging compound and photographically copying through the corrected image without removal of any of said staging compound.

7. The method of controlled color correction of photomechanical images which comprises the steps of applying a permanent thin glossy coating of opaque, waterproof, acid-resisting staging compound to image masses from which color

values are to be deleted, then staging image masses that are correct with clear transparent waterproof, acid-resisting staging compound whereby the several masses are permanently protected, then photographically copying through the corrected image without removing any of the previously applied compounds.

8. The method of controlled color correction of halftone dry plate photomechanical images which comprises the steps of applying to those masses from which color values are to be deleted a permanent thin glossy coating of opaque, waterproof, acid-resisting staging compound, then staging halftone masses that are correct with a Celluloid base, transparent, waterproof, acid-resisting staging compound having acetone as its solvent whereby said halftone masses are simultaneously clarified and protected against subsequent chemical etching of unstaged portions of the image and finally photographically copying through the corrected image without removal of any of the previously applied compounds.

9. The method of controlled color correction of photomechanical images which comprises the steps of applying a thin permanent coating of dense opaque glossy, turpentine soluble waterproof, acid-resisting opaque staging compound to masses from which all color is to be deleted, then applying to tone masses that are correct a clear transparent waterproof acid-resisting liquid Celluloid staging compound, then applying to those tone masses requiring intensification a transparent waterproof, acid-resisting Celluloid staging compound having selected tints of actinic light retarding aniline dyes therein, then chemically etching the unstaged masses, arresting the etching from time to time and staging the correctly etched masses with said clear transparent waterproof, acid-resisting staging compound until all desired masses on the image have been corrected, then photographically copying through the image thus corrected without removal of any of the previously applied staging compounds.

10. The method of controlled color correction of photomechanical projection images which

comprises the steps of opaquing unwanted image masses with waterproof, acid-resisting glossy opaque staging compound, staging those image masses that are correct with a transparent, waterproof, acid-resisting staging compound, then staging tone masses requiring intensification with transparent waterproof, acid-resisting staging compound containing selected tints of dye of known light retarding properties, then etching with etching solution the unstaged image masses until masses requiring the least etching are correct, staging the masses thus corrected with transparent waterproof and acid-resisting staging compound, repeating the etching and staging operations as required on successive masses, stripping in desired mass tone image and line image masses where required, securing the edges of such stripped in masses with waterproof, acid-resisting staging compound, then photographically copying through the image masses thus corrected by projection onto a sensitized metal printing plate without removing any of said staging compounds, thereby eliminating all crayon work alterations on said metal printing plate.
